W. F. KERSEY

WIRE SPLICER

Filed March 7, 1927

Inventor

William F. Kersey

By Clarence A. O'Brien
Attorney

UNITED STATES PATENT OFFICE.

WILLIAM F. KERSEY, OF LEBANON, OHIO.

WIRE SPLICER.

Application filed March 7, 1927. Serial No. 173,570.

The present invention relates to an improved tool or implement such as is commonly known in the trade as a wire splicer, the same having more particular reference 5 to a tool which is particularly constructed for bending and twisting together the ends of two wires in order that they may be securely connected together.

Briefly, the invention comprises a handle 10 having a pair of spaced parallel plates riveted to its outer end, there being a slotted ratchet wheel rotatably mounted between the plates, a double acting pawl mechanism for regulating the action of the ratchet 15 wheel, and the ratchet wheel being provided with outstanding apertured lugs in which the bent end of one wire is fastened.

My principal aim is to generally improve upon wire splicing implements of this class 20 by providing one wherein the parts are so associated and connected, as to insure practicability and efficiency in operation and use.

The particular details and method in 25 which they are associated with each other, will become more readily apparent from the following description and drawings.

In the accompanying drawings:—

Figure 1 is a side view of a wire splicing 30 tool constructed in accordance with the present invention.

Fig. 2 is a top plan view of the same.

Fig. 3 is a front end elevation.

Fig. 4 is a fragmentary view, showing the 35 internal construction more plainly.

Fig. 5 is a perspective view showing the approximate method of use.

Referring to the drawing in detail, it will be seen that 1 represents the handle which 40 is in the form of a flat bar having a notch 2 (Fig. 4) formed at its outer end and the notch operating as a socket for reception of a coiled spring 3. This coiled spring surrounds a rivet 4 carried by the central portion of a plate 5, this plate being slidably mounted between a pair of spaced parallel side members 6, which are riveted to and extend beyond the outer end of the handle.

These side members are provided with circular openings in which the journals of a 50 rotatably mounted ratchet wheel 7 are arranged. Obviously, the ratchet wheel is provided with suitable ratchet teeth, and in this connection it is provided with a keyhole 55 shaped slot 8 adapted to register with an entrance slot 9 for the fence wire 10. A pair

of oppositely disposed pawls 11 are pivotally supported between the side members, each pawl having its nose engaged with the ratchet teeth and having its opposite inner 60 end shaped and flattened as at 12, to bear against the spring pressed plate 5.

It will be noticed that the ratchet wheel is provided with a pair of oppositely extending apertured lugs 13, which obviously serve 65 to receive the bent end 14 of the complementary wire 15.

In using the device, I employ a suitable wire clamp 16 of the type represented in dotted lines in Fig. 5. This is engaged with 70 the two wires which are arranged in the association shown in Fig. 5. The bent end 14 of the wire 15 is extended through the aperture in the lug 13, while the wire 10 is arranged in the keyhole slot 8. Obviously 75 by moving the handle back and forth, in a customary manner, the ratchet and pawl mechanism will serve to wrap the wire 10 about the wire 15 as indicated at 17 in Fig. 5.

It is believed that by considering the description in connection with the drawings, a clear understanding of the construction and operation of the invention will be had. Therefore, a more lengthy description is 85 thought unnecessary.

While the preferred embodiment of the invention has been shown and described, it is to be understood that minor changes coming within the field of invention claimed 90 may be resorted to if desired.

Having thus described my invention, what I claim as new is:—

1. A wire splicer comprising a handle, a pair of side members connected to the outer 95 end of the handle and extending beyond said end in spaced parallelism and provided adjacent their outer ends with substantially circular openings, a toothed ratchet wheel located between said side members 100 and including journals rotatably mounted in said openings, said ratchet wheel being provided with a wire slot and with an outstanding integral apertured wire end receiving lug, and double-acting spring pressed 105 pawl mechanism carried by the side members and cooperable with the teeth of the ratchet wheel.

2. A wire splicer of the class described, comprising a handle provided at its outer 110 end with a notch forming a spring receiving socket, a pair of side members fastened

to opposite sides of the handle and extending outwardly beyond the outer ends of the handle in spaced parallelism, said side members being provided with a pair of oppositely disposed bearing openings, a toothed ratchet wheel located between said side members and including journals rotatably mounted in said openings, said ratchet wheel having a substantially keyhole shaped slot extending 5 radially from its center, the ends of said side members being provided with openings adapted to register with the slots, a pair of integral outwardly extending lugs carried by the peripheral portion of the ratchet 10 wheel, spring pressed pawls pivotally mounted between the side members and cooperable with the teeth of the ratchet wheel, a plate 15 slidably mounted between the side members

and engageable with the pivoted ends of the pawls, a rivet carried by the center of 20 the plate, and a coiled spring surrounding the rivet at one end and having its opposite end located in said spring receiving socket.

3. As a new product of manufacture, a wire splicing tool of the class described, comprising a handle provided at its outer end 25 with a wire entrance, a pawl and ratchet mechanism mounted upon the outer end portion of the handle and associated with said entrance, the ratchet being provided 30 with an opening for passage of one of the wires, and being further provided with a means for anchoring an adjacent end of the complementary wire.

In testimony whereof I affix my signature.
WILLIAM F. KERSEY.
